CLAIM

The ornamental design for an open front refrigerated cooler, as shown as described.

DESCRIPTION

FIG. 1 is a top view of the open front refrigerated cooler according to the present invention, with the front blind in the down position;

FIG. 2 is a back view of the open front refrigerated cooler as shown in FIG. 1;

FIG. 3 is a front view of the open front refrigerated cooler as shown in FIG. 1;

FIG. 4 is a front elevational view of the open front refrigerated cooler as shown in FIG. 1;

FIG. 5 is a right side view of the open front refrigerated cooler as shown in FIG. 1;

FIG. 6 is a left side view of the open front refrigerated cooler as shown in FIG. 1;

FIG. 7 is a top view of the open front refrigerated cooler as shown in FIG. 1, with the front blind in the up position, covering the open front;

FIG. 8 is a front view of the open front refrigerated cooler as shown in FIG. 1, with the front blind in the up position, covering the open front; and,

FIG. 9 is a front elevational view of the open front refrigerated cooler as shown in FIG. 1, with the front blind in the up position, covering the open front.

The claimed second embodiment of the design of the present invention includes registered trademarks RED BULL, as seen on the right side view, left side view, front view, and front elevational, the Double Bull Device as seen on the front view and front elevational view, both of which are owned by Red Bull GmbH.
